UNITED STATES PATENT OFFICE.

EDWARD HAMMANN, OF BROOKLYN, AND WILLIAM C. PEET, OF NEW YORK,
ASSIGNORS TO THE J. L. MOTT IRON WORKS, OF NEW YORK, N. Y.

DESIGN FOR A WATER-CLOSET COVER.

SPECIFICATION forming part of Design No. 22,449, dated May 16, 1893.

Application filed February 27, 1893. Serial No. 463,982. Term of patent 14 years.

To all whom it may concern:

Be it known that we, EDWARD HAMMANN, of Brooklyn, in the county of Kings and State of New York, and WILLIAM C. PEET, of the city, county, and State of New York, citizens of the United States, have jointly invented a new Design for a Water-Closet Cover, of which the following is a specification.

The leading feature of this design consists in the rounded back corners and curved edges of the seat.

In the accompanying drawings, Figure. 1 is a plan and Fig. 2. an elevation of the seat and lid.

The front and sides of the lid and seat are

elliptical at *a. b.* the back corners are rounded at *c. d.* and the intermediate portions of the sides are concave at *e. f.* The rear of the seat plate is concave at *g.* The edges of the seat are rounded as shown in the elevation Fig. 2.

We claim—

The design of the water closet cover substantially as described and shown.

Signed by us this 23d day of February, 1893.

EDWARD HAMMANN.

WILLIAM C. PEET.
